Des. 225,298
Patented Dec. 5, 1972

225,298

ORBITAL SANDER

Melvin H. Boldt, Glenview, Ill., assignor to G. W.
Murphy Industries, Inc., Houston, Tex.

Filed Oct. 16, 1970, Ser. No. 25,521

Term of patent 14 years

Int. Cl. D8—05

U.S. Cl. D8—62

Fig-1

Fig-2

Fig-3

Fig-4

Fig-5

FIG. 1 is a top plan view of an orbital sander, showing my new design;

FIG. 2 is a left side elevational view of the orbital sander illustrated in FIG. 1;

FIG. 3 is a front elevational view of the orbital sander illustrated in FIG. 1;

FIG. 4 is a rear elevational view of the orbital sander illustrated in FIG. 1; and

FIG. 5 is a bottom plan view of the orbital sander illustrated in FIG. 1.

I claim:

The ornamental design for an orbital sander, substantially as shown.
